UNITED STATES PATENT OFFICE.

PHILIP MUELLER AND ANTON C. SCHUERMANN, OF DECATUR, ILLINOIS, ASSIGNORS TO
ADOLPH MUELLER, TRUSTEE, OF DECATUR, ILLINOIS.

POP-UP WASTE.

Application filed May 8, 1923. Serial No. 637,525.

The present invention relates to a waste stopper mechanism for bowls, lavatories and other analogous receptacles.

One of the salient features of the present development is the provision of a simple and comparatively inexpensive stopper operating mechanism having those parts requiring adjustment arranged exteriorly of the casing, so that the necessary adjustments can be made with greater facility than where the adjusting parts are positioned interiorly of the casing.

Heretofore in fittings of this type, the waste stopper, in order to effectively insure a proper operating of the parts, has been of considerable length and extended a considerable distance into the casing, thus requiring a proportionate lengthening of the casing.

In the present development, the operating mechanism has been so simplified as to very materially shorten the length of the waste stopper and casing, thus not only effecting a considerable saving in the amount of metal required, but also greatly enhancing the appearance of the installation by giving the casing and its associated parts a more compact arrangement than has previously been possible in similar fittings.

In the accompanying drawings we have illustrated one embodiment of our invention, and

Fig. 1 is a vertical sectional view of our improved waste stopper and operating mechanism shown installed on a vitreous lavatory.

Fig. 2 is a sectional view taken on the line 2—2 of Fig. 1.

Fig. 3 is a detail end view of the operating yoke.

Fig. 4 is a view taken on the line 4—4 of Fig. 2.

Fig. 5 is a detail bottom plan view of the waste stopper.

Referring to the drawings wherein like numerals indicate like parts in the various views, 10 indicates a bowl or lavatory, preferably composed of vitreous ware which may be of any suitable or desired design and dimensions, and having the usual overflow passage 11 suitably connected to the waste outlet in the bottom of the bowl.

A sleeve fitting 12 having an externally screw threaded portion passes through the waste outlet and extends below the bottom of the bowl 10, to which it is secured by the 55 gasket 13 and the nut 14. The upper end of the sleeve 12 is provided with a peripheral flange 15 adapted to engage a packing 16, putty or cement, preferably being seated in an enlarged recess in the bottom of the 60 bowl to finish any uneven surface and prevent the accumulation of filth. It will be observed that the packing 13 and 16 tends to insure a fluid tight connection and eliminate the possibility of the waste water seeping 65 through the opening in the bottom of the bowl. If desired the packing 13 may be recessed and a metal packing retaining ring 13' inserted in the recess to prevent the inner edge of the packing from being forced into 70 the waste opening of the bowl.

To the lower end of the sleeve 12 is secured, preferably by engaging the threaded portion of the sleeve, the adjustable casing 75 17 which is provided with the offset chamber 18 extending outwardly therefrom. To the open lower end of the casing 17 is threaded or otherwise suitably secured a plug 20, to which is suitably connected the end of the trap 21.

A hollow tubular stopper 22 is telescopically mounted in the sleeve 12 and projects a short distance within the casing 17. The upper end of said stopper 22 being formed with a conical head 23 adapted to be seated 85 against a correspondingly conical seat formed in the end of the sleeve 12, so as to provide a water tight joint when the stopper is in closed position. In order to permit passage of water from the bowl to the waste outlet, the stopper 22 is provided with a plurality of wall slots 24 adjacent the conical head 23. The stopper 22 is maintained in position and prevented from being removed from the sleeve 12 by means of a longitudinal 95 slot 25 which is engaged by a screw 26 threadedly secured to the casing 17. The lower end of the stopper 22 has formed about the outside thereof diametrically opposed interrupted grooves 27 having flat 100 sides 28, as shown in Figs. 2 and 5, so as to permit the ready removal of the stopper

from the casing when it is rotated to bring the flat sides in line with the actuating fork, presently to be described.

The offset chamber 18 receives the inner

5 end of a lifting fork 29, the arms 30 of said fork being provided with the inwardly extending pins or rollers 31 adapted to loosely engage the interrupted grooves 27 in the stopper 22.

10 With this construction, it will be seen that when it is desired to remove the stopper 22 from the bowl, the same is easily accomplished by withdrawing the screw 26 from the slot 25 and turning the stopper so as to 15 have the flat sides 28 thereof in alignment with the pins 31, which will then permit the stopper to be easily lifted from the bowl.

15 A fork-supporting and operating pin 32 is transversely mounted in bearings formed 20 in the walls of the offset portion of the chamber 18, said pin 32 preferably being formed with a squared enlargement 33 which is adapted to engage a correspondingly squared opening 34 formed in the inner end of the 25 lifting fork 29. A gland, formed by packing 35 and nut 36, as shown in Fig. 2, is provided to prevent leakage past the pin, 32.

An operating yoke 37 is rotatably secured 30 to one wall of the chamber 18 by the threaded pin 38 while its opposite arm is formed with an opening 39, having an open slot 39' to permit the entrance into the opening of the flattened end 40 of the pin 32 which is held by means of the set screw 41. 35 It will be seen that the slot 39' is slightly less in width than the diameter of the opening 39, so as to form a pocket 39' for receiving the circular portion of the flattened end of the pin, and thus prevent its escape therefrom when held by the set screw 41. The 40 yoke 37 between its ends is provided with lugs 42 having apertures 43 which are adapted to be loosely engaged by an operating member 44 by means of the removable pin 45.

The operating member 44 has a flattened section 46 and is engaged by a slidable member 47 which is adjustably secured thereto by the set screw 48. The upper end of the member 47 is formed with a screw threaded portion 48' to which is adjustably secured the lower end of the lifting rod 49, which rod may extend upwardly and have secured to it in any suitable manner, a hand knob or other operating part (not shown).

55 By this novel construction, not only are the elements requiring adjustment positioned outside of the casing, but by means of the nut 20, access is readily had to the interior of the casing for cleansing the same or for any other purpose.

While the form of the invention herewith disclosed is a preferred embodiment of the same, it is in no sense restrictive, and may be varied as to minor features of construc-

tion and operation without departing from the spirit of the invention and the scope of what is claimed.

We claim:

1. The combination in a fitting of the class described, of a tubular waste stopper, a stopper casing into which the lower end of said stopper projects, a stopper fork engaging opposite sides of said stopper and pivotally mounted in said casing, a yoke journaled to both sides of said casing, and means connected to said yoke and engaging said fork for actuating said stopper; said yoke, fork, and their operating means being arranged symmetrically with respect to one another so as to give a uniformly distributed lifting action.

2. The combination in a fitting of the class described, of a waste stopper casing having a laterally offset chamber, a tubular waste stopper in said casing, a stopper lifting fork pivotally mounted in said chamber and engaging opposite sides of said stopper, a yoke journaled to both sides of said chamber, and means transversely disposed in said chamber to connect said yoke and said lifting fork; said yoke, fork, and their operating means being arranged symmetrically with respect to one another so as to give a uniformly distributed lifting action.

3. The combination in a fitting of the class described, of a waste stopper casing having a laterally offset chamber, a tubular waste stopper in said casing, a stopper lifting fork engaging opposite sides of said stopper and projecting into said offset chamber, a transversely disposed pin pivotally mounted in said chamber and operatively connected to said lifting fork, a yoke connected to said offset chamber and transverse pin, and manual means for operating said yoke, said yoke and fork and their operating means being arranged symmetrically with respect to one another so as to give a uniformly distributed lifting action.

4. The combination in a fitting of the class described, of a waste stopper casing having an offset chamber, a tubular waste stopper in said casing, a stopper lifting fork engaging opposite sides of said stopper and projecting into said offset chamber, a transversely disposed pin pivotally mounted in said chamber, a yoke embracing said chamber and operatively connected to said pin, an arm loosely connected at one end to said yoke, and a vertical lifting rod adjustably secured to said arm; whereby a uniformly distributed lifting action is imparted to the stopper when the lifting rod is actuated.

5. The combination in a fitting of the class described, of a waste stopper casing having an offset chamber, a tubular waste stopper in said casing, a stopper lifting fork engaging opposite sides of said stopper and projecting into said offset chamber, a trans-

- versely disposed pin pivotally mounted in said chamber, a yoke embracing said chamber and operatively connected to said yoke, and a lifting rod adjustably connected to 5 said arm; whereby a uniformly distributed lifting action is imparted to the stopper when the lifting rod is actuated.
6. In a fitting of the class described, the combination of a stopper casing having an offset chamber, a stopper actuating fork pivotally mounted in said offset chamber and projecting into said casing, actuating means for said stopper fork mounted in said offset chamber, a yoke embracing said offset chamber and engaging the actuating means for said stopper fork, one arm of said yoke having an open slot therein, manual means for operating said yoke, means removably securing said actuating means to said yoke; 10 said yoke, fork, and their operating means being arranged symmetrically with respect to one another so as to give a uniformly distributed lifting action.
7. In a fitting of the class described, the combination of a stopper casing having an offset chamber, a stopper actuating fork pivotally mounted in said offset chamber and projecting into said casing, a transversely disposed pin projecting into said chamber 15 and operatively connected to said fork, a yoke embracing said offset chamber and engaging said pin, one arm of said yoke having an open slot therein and being removably secured to said transverse pin, and manually 20 adjustable means for operating said yoke; said yoke, fork, and their operating means being arranged symmetrically with respect to one another so as to give a uniformly distributed lifting action to said stopper.
- 40 8. The combination in a fitting of the class described, of a waste stopper casing, a waste stopper in said casing, a lever pivoted to said casing and operatively connected to said stopper, an arm pivoted to said lever, a vertically disposed lifting rod, a link threaded 45 on said lifting rod and slidably associated with said arm, and means for permitting the arm to be adjusted horizontally relative to said rod.
- 50 9. The combination in a fitting of the class described, of a waste stopper casing, a waste stopper mounted in said casing, stopper actuating means mounted in said casing, a 55 yoke journalled to opposite sides of said casing and operatively connected to said actuating means, and operating means loosely connected to the medial portion of said yoke.
10. The combination in a fitting of the class described, of a waste stopper casing, a 60 waste stopper mounted therein, a member pivotally mounted in said casing and engaging opposite sides of said stopper, and actuating means for said member arranged symmetrically with respect thereto to give a 65 uniformly distributed lifting action.
11. The combination in a fitting of the class described, a waste stopper casing, a waste stopper mounted therein, a stopper fork pivotally mounted in said casing and 70 engaging opposite sides of said stopper, and a yoke journalled to opposite sides of said casing and operatively connected to said fork.
12. The combination in a fitting of the class described, of a waste stopper casing, a waste stopper mounted therein, stopper actuating means pivotally mounted in said casing, a yoke journalled to said casing, means connecting said yoke with said stopper 80 actuating means, an arm of said yoke being slotted to receive part of said connecting means, and means for releasably securing said slotted arm to said connecting means.
13. A fitting comprising a waste stopper 85 casing having a lateral chamber, a waste stopper mounted in said casing, a stopper fork engaging said stopper and pivotally mounted in said lateral chamber, and a yoke journalled to said chamber and operatively 90 connected to said fork.
14. A fitting comprising a stopper casing, a waste stopper mounted therein, stopper actuating means having a non-circular opening, a yoke having one arm removably and 95 pivotally connected to said casing, the other arm of said yoke being slotted, and a pin removably journalled in said casing and having a non-circular portion to fit the non-circular opening of the actuating means, and 100 being adapted to be removably engaged with the slotted arm of said yoke.

In testimony whereof we have hereunto set our hands.

PHILIP MUELLER.
ANTON C. SCHUERMANN.
